WAX SPREADER

George H. Wallis, P.O. Box 177, Barrington, Ill.

Filed Oct. 8, 1959, Ser. No. 845,180

3 Claims. (Cl. 15—546)

This invention relates to a liquid wax spreader for floors.

The principal object of this invention is to spread a self-polishing liquid wax and wipe it just once to provide a uniform thickness of wax on a floor, and particularly a thin coating of wax. Maintenance of floors, such as the various plastic tile floors, in establishments where there is heavy foot traffic as well as movements of various types of vehicles such as grocery carts and pallets for loading commodities on shelves in chain stores, calls for washing the floor at least twice a week and waxing at least once. Many times, this is done much more frequently as the wax protects the floor.

The first specific object of this invention is to apply liquid wax along a line under pressure so that it immediately penetrates the crevices in the floor and then to wipe the wax once by a pad under selected pressure. The pressure on the pad will largely control the thickness of the wax left on the surface.

An object ancillary to the foregoing is to eliminate the effect of changes in weight of the spreader during application. A spreader has a wax reservoir, and whether the wax is under pressure or not, as the reservoir empties, it becomes lighter. If the weight of the reservoir has anything to do with the applicator pad, it will apply a thicker film of wax as the reservoir gets lighter. A feature of applicants spreader is mounting a pressure tank for liquid wax on a two-wheel frame with the wax applicator and spreading pad independently suspended on a bracket so that the downward pressure on the pad is constant because the weight of the bracket does not vary.

Another object of the invention is to relate the wax-spreading and pad carriage adjustably to the frame so that the operator may draw the spreader along the floor at whatever angle is natural for him. A feature of the invention is a ratchet device on the bracket carrying the spreader for setting its angle with respect to the main carriage at any of several points.

Another object of the invention is to arrange a finger control for a wax applicator valve, and a finger control for the bracket carrying the spreader adjacent a handle so that an operator can pull the spreader and control both wax and pressure to meet the particular needs, i.e., open floor against moving under a counter.

Another object of the invention is to provide a spray tube and pad extending laterally beyond the limits of the frame so that waxing may be done under counters.

These and such other objects as may hereinafter appear are attained in the embodiment of the invention shown in the accompanying drawings, wherein:

Figure 1 is a front perspective view of the wax spreader, in operating position;

Figure 2 is a back view of the machine, showing especially the manual controls;

Figure 3 shows a side view of the machine in a rest position, with a section along the line 3—3 of Figure 1, of the adjustable arms;

2

Figure 4 shows an arm with a ratchet and a spray rod attachment; and

Figure 5 is a side section of the spreader pad.

As shown in Figure 1, the frame comprises essentially 5 a U-shaped tubular bar 1, the lower ends of which are secured to an axle 2. A wheel 22 is mounted on each end of the axle 2. A handle 3 is mounted on the upper part of the frame. Upper and lower arcuate bands 4 and 5 form a cradle for a pressure tank 8. At the base 10 of the frame is positioned a circular pan 6 with a narrow rim, and the whole is supported on the axle 2. The tank 8 removably rests on the pan 6 and against the bands 4 and 5. The tank 8 is held in the cradle by brackets and wing bolt assemblies 17. A support 7, being a tube attached to the pan 6, holds the whole upright when the weight is canted forwardly of the axle 2.

The liquid reservoir comprises a cylindrical tank 8, having on the uppermost surface a funnel 9 housing the handle 10 of a hand pump (not shown) located within 20 the tank, but removable by a twist of the handle. By removing the handle 10, liquid wax may be poured into the tank. A removable top 11, secured by clamps 12 to the tank, allows cleaning of the tank. A pressure gauge 13, adjacent to said funnel, projecting through the 25 removable top into the tank is provided. A delivery tube (not shown) within the tank, extending from near the bottom of the tank upwardly connects with a nipple 14 in the top and to a delivery tube or hose 15 leading downwards to a valve 16 which controls flow of wax into 30 a flexible hose 28.

Referring to Figure 3, two arms 18 project forwardly from the axle and with cross brace 25 form a bracket. As shown in Figure 4, a pivoted lock arm 23 fixes the 35 arms 18 to the axle and allows for the easy detachment of the bracket from the frame. Formed integrally with each arm is a ratchet having notches 19. The notches 19 are so positioned as to engage a pawl 20 sliding in brackets 21 mounted on each leg of the tubular U-bar.

Mounted on the arms 18 forward of the axle 2 is an 40 elongated spray tube 26, parallel to the axle and laterally projecting beyond the narrow wheeled frame, with numerous downwardly directed ports 50. The hose 28 connects to a fluid coupling 27 opening into the spray tube 26. A removable eye bolt 46 holds the spray tube 45 26 on the underside of each arm 18.

At the outer ends of the arms 18 and coextensive laterally with the spray tube is detachably mounted a wax spreader 29. As shown in Figure 5, the spreader consists of two plywood strips 31 and 32 between whose 50 longitudinal lengths is clamped a piece of lambswool 33 drawn over a compression pad, usually of rubber, 30.

Returning to Figure 3, a finger control comprises two rods 35 and 36 with ring grips. The finger grips are positioned immediately below the handle 3 on a bracket 55 37. The rod 35 extends downward and is attached to a lever 38 which functions the valve mechanism 16. This valve controls the flow of wax from the tank 8 to the spreader tube 26. The valve 16 is mounted on a bracket 39 to one leg of the U-bar.

Referring to Figure 2, the second rod 36 extends downward through a groove 40 on the upper band 4 to one arm of a double bell crank lever 41, centrally pivoted on the lower of the two bands 5. Two links 42 are connected to the ends of this lever 41 and are connected respectively 60 to bell crank levers 43, pivotally mounted on opposite ends of the band 5. The second arm of each of the two bell crank levers 43 is connected to a rod 44 having the lower portion bent to act as a pawl 20 to engage notches in the ratchet 19. By said successive levers and rods, the inside rod 36 controls the movement of the two pawls 20. A spiral spring 45 enclosed in each bracket 21 urges the rods 43 and 44 downwardly so as to engage the de-

sired notch of the ratchets 19, until withdrawn by the lifting of the innermost plunger rod by the finger grip. Since the ratchets govern the spreader arms, the raising and lowering of the spreader and the spray tube, or conversely, the raising and lowering of the wheeled frame, is easily done.

Having thus described his invention, what applicant claims is:

1. A wax spreader comprising a frame, an axle mounted on said frame near its base, a wheel on each end of said axle, a cradle on said frame for holding a pressure tank, a bracket pivotally mounted on said frame near the axle and extending to one side of the axle, a straight spray tube mounted horizontally on said bracket and generally parallel to the axle, downwardly directed openings through the wall of said tube for its entire length, an intake port into said tube, a valve mounted on said frame, a flexible tube connecting the delivery port of the valve to the port on the spray tube, a spreading pad mounted on said bracket substantially parallel to said spray tube and coextensive in length, and means for holding the pivoted bracket in fixed relationship to the frame at one of a plurality of angles with respect to the frame.

2. A wax spreader comprising an inverted, U-shaped frame, an axle mounted on the free ends of said frame, a wheel at each end of said axle, an arcuate band mounted between the arms of said frame so that an upright cylindrical pressure tank may be supported on the axle and rest against the band, an arm pivotally mounted on

the axle near each end, a straight spray tube rigidly mounted on the two arms and spaced from the arm ends substantially parallel to the axle and in a horizontal position, downwardly directed delivery ports in the wall of said spray tube, an intake port on said spray tube, a valve mounted on said frame, a flexible conduit connecting the delivery port of the valve to the intake port of the spray tube, an elongated, downwardly directed pad mounted on the outer ends of said arms, said pad being coextensive in length with the spray tube, a ratchet having notches mounted on the axle end of each arm, and a detent mounted on each arm of the frame and engageable with a notch.

3. The spreader of claim 2 together with a handle mounted on the upper part of the U-shaped frame and extending in a direction opposite to the arms carrying the spray tube and pad, a finger control adjacent said handle for functioning the valve, and a second finger control adjacent said handle for controlling the means for changing the angle of arms carrying the spray tube and pad with respect to said frame.
